[57] CLAIM

The ornamental design for support pedestal for a table,
as shown and described in FIGS. 1-4.

DESCRIPTION

FIG. 1 is a perspective view of a support pedestal for a
table, showing my new design:

FIG. 2 is a top plan view;

FIG. 3 is a side elevational view, the opposite side being
identical thereto; and,

FIG. 4 is an end elevational view, the opposite end
being identical thereto.

FIG. 1

FIG. 2

FIG. 3

FIG. 4
